W. A. FITZSIMMONS

ELECTRIC CATCHER AND CONVEYER

Filed Dec. 4, 1923

Patented Oct. 21, 1924.

1,512,413

UNITED STATES PATENT OFFICE.

WILLIAM A. FITZSIMMONS, OF CANTON, OHIO.

ELECTRIC CATCHER AND CONVEYER.

Application filed December 4, 1923. Serial No. 678,410.

To all whom it may concern:

Be it known that I, WILLIAM A. FITZSIMMONS, a citizen of the United States, residing at Canton, in the county of Stark 5 and State of Ohio, have invented certain new and useful Improvements in Electric Catchers and Conveyers, of which the following is a specification.

This invention relates to mechanism for 10 catching sheets of steel and the like as they emerge from cold rolls, shears, bucklers, presses, stamping machines, and other machines through which cold sheets are passed; and for conveying the sheets away from the 15 machine and depositing them in any desired place.

The objects of the improvement are to provide a machine of this character having an endless belt carrying electro-magnets arranged to catch each sheet as it emerges from the cold rolls or other machine and carry the sheet away from the machine and deposit it at a suitable place away from the machine.

Although the improved catcher and conveyor may be applied to numerous sheet handling machines, for the purpose of illustration it is shown applied to a cold rolling mill in the accompanying drawings, in which—

30 Figure 1 is a side elevation of the electric catcher and conveyer attached to a cold rolling mill;

Fig. 2, a fragmentary plan view of a portion of the endless belt which carries the magnets;

Figs. 3 and 4, detail views of the pulleys over which the belt travels; and

Fig. 5, a section on the line 5—5, Fig. 1.

Similar numerals refer to similar parts 40 throughout the drawings.

A portion of the housing of a cold rolling mill is shown at 1 and the rolls thereof at 2, the usual table 3 being located in position to receive the sheets upon the fiber rollers 45 4, as they emerge from the rolls of the mill.

The improved catcher is mounted in a frame comprising the side members 5 connected together in suitable manner and provided with the notches 6 at one end for engagement with the rest bar 7 of the mill,

50 the other end being preferably provided with uprights 8 to which are connected suspension braces 9, which may be attached to the housings of the mill.

55 A platform 10 is supported upon the side members 5 and carries a motor 11 having a

pinion 12 upon its shaft meshing with a gear 13 upon a countershaft 14. A sprocket 15 is fixed upon the shaft 14 and connected by the sprocket chain 16 with a similar 60 sprocket 17 fixed upon the shaft 18 of the pulley 19.

This pulley is preferably provided with an insulated periphery and carries a conductor ring 20 near one side thereof. A 65 similar pulley 21 is located at the forward end of the frame and provided with a conductor ring 22 located near the other side, an endless belt 23 being located around said pulleys and provided with the woven wire 70 conductors 24 and 25, arranged to engage the conductor rings 20 and 22 respectively.

Electro-magnets 26 are connected at close intervals to the belt 23, each magnet being connected to both of the conductors 24 and 25. A brush 27, connected to one side of an electric circuit, is permanently held in contact with the conductor ring 22 upon the pulley 21.

A brush 28 is mounted for slidable movement upon the frame and connected by a link 29 with the upper end of a lever 30 pivoted intermediate its ends as at 31 to the frame, and arranged to normally hang in the vertical position, as shown in Fig. 1, 85 holding the brush 28 out of contact with the conductor ring 20 of the pulley 19.

A fiber roller 32 is journaled upon the lower end portion of the lever 30 in the path of sheets emerging from the rolls of 90 the mill.

As the forward end of each sheet passes over the rollers 4 upon the table 3 and contacts with the fiber roller 32 upon the lever 30, the lever will be tilted by the sheet, 95 permitting the same to pass under the roller 32, this tilting of the lever moving the brush 28 into contact with the conductor 20 of the pulley 19 and since this brush is connected to the other side of the electric 100 circuit above referred to, it will be seen that the circuit will be closed through the conductors 24 and 25 of the endless belt, energizing the magnets.

As the sheet continues to move forward, 105 it will be engaged by the magnets and held suspended thereby until the rear end of the sheet passes from beneath the roller 32, when the lever 30 will, by gravity, move back to its normal position, disengaging the 110 brush 28 from the conductor ring 20, breaking the circuit through the conductors 24

and 25, and deenergizing the magnets, permitting the sheet to be dropped upon the floor or upon any suitable rack or support which may be provided for the same beneath the device.

From the above, it will be seen that the sheets as they emerge from the rolling mill or other machine, trip the mechanism which automatically energizes the electro-magnets 10 causing them to attract the sheet as it passes beneath the same, carrying the sheet to the desired point where the magnets are automatically deenergized by the sheet passing out of engagement with the fiber roller 15 upon the lever 30, thus obviating the necessity of providing an operator for the catcher and conveyer.

I claim:—

1. A catcher and conveyer for receiving 20 moving sheets, including an endless belt, magnets upon the belt adapted to attract the sheets, and means operated by the movement of the sheet for automatically energizing the magnets.
2. A catcher and conveyer for receiving 25 moving sheets, including an endless belt, magnets upon the belt adapted to attract the sheets, and means operated by the movement of the sheet for automatically energizing the magnets at a predetermined point and deenergizing the magnets at a predetermined point.
3. A catcher and conveyer for receiving 30 moving sheets, including an endless belt, electro-magnets upon the belt, a movable brush for closing the circuit to said magnets, and a pivoted lever operatively connected to the brush and located in the path of the sheets.
4. A catcher and conveyer for receiving 40 moving sheets, including an endless belt, electro-magnets upon the belt, a movable brush for closing the circuit to said magnets, a pivoted lever operatively connected to the brush and located in the path of the 45 sheets, and a fiber roller upon said lever for engagement with the sheets.
5. A catcher and conveyer for receiving 50 moving sheets, including an endless belt having two endless conductors mounted 55 therein, pulleys over which the endless belt is located, a conductor ring upon each pulley engaging one of the conductors in the belt, a brush permanently engaging one conductor ring, a brush normally held out of engagement with the other ring, electro-magnets upon the belt connected to the conductors and means operated by the movement of a sheet for automatically engaging the last named brush with the adjacent conductor ring.

In testimony that I claim the above, I have hereunto subscribed my name.

WILLIAM A. FITZSIMMONS.
